US0D1014540S

(12) United States Design Patent (10) Patent No.: US D1,014,540 S
(45) Date of Patent:  Feb. 13, 2024

(54) DISPLAY SCREEN OR PORTION THEREOF
WITH GRAPHICAL USER INTERFACE

(71) Applicant: Aristocrat Technologies Australia Pty Limited, North Ryde (AU)

(72) Inventors: Thomas Tuomey, Las Vegas, NV (US); Jocellie Imutan, Henderson, NV (US)

(73) Assignee: ARISTOCRAT TECHNOLOGIES AUSTRALIA PTY LIMITED, North Ryde (AU)

() Term: 15 Years

(21) Appl. No.: 29/861,697

(22) Filed: Dec. 1, 2022

Related U.S. Application Data

(60) Continuation of application No. 29/794,637, filed on Jun. 14, 2021, now Pat. No. Des. 974,395, which is a division of application No. 29/662,088, filed on Aug. 31, 2018, now Pat. No. Des. 925,552.

CLAIM

The ornamental design for a display screen or portion thereof with graphical user interface, as shown and described.

DESCRIPTION

The FIGURE is a display screen or portion thereof with graphical user interface showing our new design.

The dashed broken line perimeter in the FIGURE illustrates a display screen or portion thereof and forms no part of the claimed design. The remaining dashed broken lines in the FIGURE illustrate portions of the graphical user interface that form no part of the claimed design.

1 Claim, 1 Drawing Sheet
